UNITED STATES PATENT OFFICE.

GUSTAVE STROHHAKER, OF WALLINGFORD, CONNECTICUT, ASSIGNOR TO INTERNATIONAL SILVER CO., OF MERIDEN, CONNECTICUT, A CORPO-RATION OF NEW JERSEY.

DESIGN FOR A HANDLE FOR SPOONS, FORKS, OR SIMILAR ARTICLES.

No. 38,658.

Specification for Design.

Patented July 9, 1907.

Application filed June 10, 1907. Serial No. 378,314. Term of patent 7 years.

To all whom it may concern:

Be it known that I, GUSTAVE STROHHAKER, a citizen of the United States, residing at Wallingford, in the county of New Haven and State of Connecticut, have invented a new, original, and ornamental Design for a Handle for a Spoon, Fork, or Similar Article; and I do hereby declare the accompanying drawing to be a full, clear, and exact illustration of the same, and which said drawing constitutes part of this specification, and represents a face view of a handle for a spoon, fork, or similar article.

Claim.

The ornamental design for a handle for a spoon, fork or similar article, as shown.

GUSTAVE STROHHAKER.
